OTHER PUBLICATIONS

Office Action issued by the United States Patent and Trademark office, dated Aug. 18, 2014, in connection with corresponding U.S. Appl. No. 13/788,769 (15 pages).

Primary Examiner — Mark Goodwin(74) *Attorney, Agent, or Firm* — Brian R. Pollack; Day Pitney LLP(57) **CLAIM**

The ornamental design for rod bracket, as shown and described.

DESCRIPTION

FIG. 1 is a right front perspective view of a first embodiment of a rod bracket showing my new design.

FIG. 2 is a left front perspective view thereof.

FIG. 3 is a front view thereof.

FIG. 4 is a back view thereof.

FIG. 5 is a left side view thereof.

FIG. 6 is a right side view thereof.

FIG. 7 is a top plan view thereof.

FIG. 8 is a bottom plan view thereof.

FIG. 9 is a right front perspective view of a second embodiment of a rod bracket showing my new design.

FIG. 10 is a left front perspective view thereof.

FIG. 11 is a front view thereof.

FIG. 12 is a back view thereof.

FIG. 13 is a left side view thereof.

FIG. 14 is a right side view thereof.

FIG. 15 is a top plan view thereof; and,

FIG. 16 is a bottom plan view thereof.

The broken line showing of various surface features is included for the purpose of illustrating portions of the rod bracket and forms no part of the claimed design.
